(No Model.)

J. GREEN.
LIFTING JACK.

No. 462,796.

Patented Nov. 10, 1891.

UNITED STATES PATENT OFFICE.

JOHN GREEN, OF RENOVO, PENNSYLVANIA, ASSIGNOR OF ONE-HALF TO
JOHN WARD AND JAMES H. SHEDDY, OF SAME PLACE.

LIFTING-JACK.

SPECIFICATION forming part of Letters Patent No. 462,796, dated November 10, 1891.

Application filed September 18, 1891. Serial No. 406,122. (No model.)

To all whom it may concern:

Be it known that I, JOHN GREEN, a citizen of the United States, residing at Renovo, in the county of Clinton and State of Pennsylvania, have invented certain new and useful Improvements in Lifting-Jacks; and I do hereby declare the following to be a full, clear, and exact description of the invention, such as will enable others skilled in the art to which it appertains to make and use the same.

My invention relates to lifting-jacks, and has for its object certain improvements in construction, which will be hereinafter fully disclosed in the following specification and claims.

In the accompanying drawings, which form part of this specification, Figure 1 represents a side view; Fig. 2, a vertical section; Fig. 3, a perspective of the head of the rack-bar; Fig. 4, a side view of the web of the frame, and Fig. 5 an end view of the same.

Reference being had to the drawings and the letters thereon, A indicates the frame or body of the lifting-jack, which is provided with base *a*, a central web *b*, which is mortised in the base *a*, as shown in Figs. 2 and 4, and sides *c c*, secured to the web *b* by bolts or rivets *d*, the whole being preferably made of hard wood to produce a very cheap, light, and yet a strong and serviceable implement. It is obvious, however, that the body may be made of cast-iron, or the web and base may be cast-iron and the sides of rolled plate.

Within the body A is a vertical slot *e* to receive a rack-bar B, and a pocket *f* to receive a pinion C and one end of an operating-lever D. The outer end *g* of the lever is preferably made of wood, and to its front end are attached metal plates or extensions *h h*, between which the pinion C is supported upon a pin or bolt *i*, which passes through the sides *c c*, plates *h h*, and the pinion and forms a fulcrum for the lever D. Between the plates *h h* is pivotally secured a pawl or latch *k* by a pin *l*, and which engages the pinion C below its axis, is operated by its handle or extension *m*, and held in operative contact with the pinion by a spring *n*, secured to the end of the lever D. Above the pinion in the pocket *f* is pivotally secured another pawl or

latch *o* by a pin *p*, and which engages by gravity with the pinion C above its axis. The pawls or latches engaging with the pinion lock the jack effectually and are in position for ready and easy manipulation in lowering bodies. In the act of raising a body the pawls both engage automatically with the pinion; but in lowering a body the lever D is moved to its lowest position, with the pawl *k* in engagement with the pinion, the pawl *o* is disengaged from the pinion, and the lever raised, which will permit the rack-bar to descend while the lever is ascending. When the lever has reached its highest point, the pawl *o* is put in engagement with the pinion, the pawl *k* released, and the lever D lowered and its pawl *k* allowed to again engage the pinion, when the foregoing operation is repeated until the body has been lowered to any desired position.

E indicates a detachable hook, the vertical arm *q* of which is provided with perforations *r*, and upon which is adjustably secured a jaw *s* by a pin *t*, which passes through holes in the lugs *u* on the inner end of the jaw and the perforations *r* in the arm *q* of the hook.

The lifting-jack is especially designed for railroad use and the hook adapted to engage a rail on a track or bridge-timbers to be raised from the ground or trestle-work, but is applicable to general use. When used upon painted work, a non-metallic pad *v*, of wood or other suitable material, is interposed between the head *w* of the rack-bar and the object to be operated upon. The pad may be held in place on the head *w* by pins or other suitable devices, which it is not considered necessary to illustrate.

Having thus fully described my invention, what I claim is—

1. In a lifting-jack, the combination of a rack-bar, a lever, a pinion attached thereto and engaging said rack-bar, and pawls engaging the pinion above and below its axis, one of said pawls being supported by the lever and the other by the frame of the jack.

2. In a lifting-jack, the combination of a rack-bar, a lever, a pinion attached thereto and engaging the rack-bar, a pawl pivotally secured to the lever and held in engagement

with the pinion below its axis, and a gravity-pawl pivotally secured to the body of the jack and engaging the pinion above its axis.

3. In a lifting-jack, the combination of a rack-bar, a lever, a pinion attached thereto and engaging the rack-bar, a hook engaging the head of the rack-bar and provided with perforations in the vertical arm thereof, an adjustable jaw having a mortise in its inner end and holes in the lugs, and a pin for securing the jaw to the arm of the hook.

4. In a lifting-jack, the combination of a rack-bar, a lever having metallic extensions

on its inner end, a pinion between said extensions and engaging said rack-bar, a spring-actuated pawl pivotally secured between the extensions, and a gravity-pawl pivotally secured to the frame of the jack and engaging the pinion above its axis. 15

In testimony whereof I affix my signature in presence of two witnesses.

JOHN GREEN.
